(57) **CLAIM**

The ornamental design for a bathroom faucet attachment, as shown and described.

DESCRIPTION

FIG. 1 is a front perspective view of the bathroom faucet attachment showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side view thereof;

FIG. 7 is a right side view thereof; and,

FIG. 8 is a front view of the attachment in relation with the bathroom faucet.

The broken line showing of a faucet is included for the purpose of illustrating environment and forms no part of the claimed design.
